UNITED STATES PATENT OFFICE.

DANIEL MASOR, OF NEW YORK, N. Y.

EXPANSION-BOLT.

1,066,512.

Specification of Letters Patent.

Patented July 8, 1913.

Application filed December 3, 1912. Serial No. 734,749.

To all whom it may concern:

Be it known that I, DANIEL MASOR, a citizen of the United States, residing at New York city, in the county of New York 5 and State of New York, have invented new and useful Improvements in Expansion-Bolts, of which the following is a specification.

This invention relates to expansion bolts 10 and has for its object to provide a comparatively simple and inexpensive device of this character, with but few parts and which, when assembled together, will not become separated and lost during shipment.

15 To these ends the invention consists in the novel details of construction and combination of parts more fully hereinafter described and particularly pointed out in the claims.

20 Referring to the accompanying drawings forming a part of this specification in which like numerals designate like parts in all the views:—Figure 1 is a sectional view of a wall and showing my improved bolt secured in position thereon. Fig. 2 is a cross sectional view of the bolt taken on the line 2—2 of Fig. 1. Fig. 3 is a cross sectional view of the bolt taken on the line 3—3 of Fig. 1. Fig. 4 is a view showing the bolt 25 removed from the wall and in its contracted position. Fig. 5 is a view showing a modified form of my improved bolt. Fig. 6 is a view showing another modification of the pivoted end of the bolt. Fig. 7 is a view 30 showing a still further modification of the pivoted end of the bolt.

35 My improved bolt is intended for securing objects to stone, ceramic or similar types of walls where the ordinary bolt is unfit for 40 accomplishing this purpose.

In Fig. 1 the stone or ceramic wall *a* is shown provided with a hole *b* in which is secured my improved expansion bolt *c* for securing to the face of a wall a portion of an object *d*. The bolt comprises a pair of 45 opposed jaw members 1 and 2 provided with the inner hollow portions 3 which taper off at their bottom as indicated at 4. At the top portion of the jaw member 2 and on 50 each side thereof, are formed circular and countersunk projections 5 in which are held a pivot pin 6. Projecting hooks 7 formed on the top portion of the jaw member 1, are mounted within the countersunk projections 55 and are arranged around the pivot pins 6.

Locking pins 8 mounted within the countersunk portions of the jaw member 2 contact with the outer edges 9 of the hooks 7 and prevent the accidental opening of the jaws until the bolt is operated. Through the jaw members is inserted a screw threaded bolt 10 provided at its upper end with the usual head 11 and secured to its lower or screw threaded end, is a tapering nut 12 which is provided with a pair of opposed and radially extending lugs 13. These lugs are adapted to operate within the openings 14 formed by the tapering edges 15 in the sides of the jaw members 1 and 2. Projecting lugs 16 formed on the lower portions of one 70 of the pivoted jaw members and arranged for contacting with the cut away portions 16' of the opposite jaw member, are provided for contacting with the lugs 13, of the tapering nut and preventing the same from 75 becoming detached from the pivoted jaw members during shipment. Straight beveled portions 17 are also provided on the sides of the nut 12 for slidably contacting with the straight portions 18 on the inside 80 of the pivoted jaw members for preventing the jaw members and tapering nut from turning when the head of the threaded bolt is operated.

It is to be noted that both of the expanding jaw members are roughened and bowed on their outer surfaces which permits of a uniform contact with the wall of the drilled hole when they are secured to position. The outer surfaces of the jaw members are also 90 provided with the straight but roughened side portions 19 which prevent the jaw members from turning within the drilled hole when the bolt is operated.

A collar 20 formed on the upper ends of 95 the expanding jaws strengthens that pivoted portion of the bolt and further assists in forming a neat and flush joint at the union of the bolt and drilled hole at their exposed ends.

In the modification shown in Fig. 5 both the projecting and hook portions 20 and 21 of the jaw members, are shown of different shape and the hook portion 21 is provided with an opening 22 through which the pivot pin 23 projects. A second pin 24 is arranged for contacting with the inner side of the hook 21 and thereby preventing the accidental opening of the jaw members until the bolt is operated. The lugs 25 and 26, mount- 110

ed on the lower ends of the pivoted jaw members, and which contact with the lugs mounted on the tapering nut, are formed to overlap each other as is clearly shown.

- 5 In the modification shown in Fig. 6, the hook 27 is provided with a cut-away top portion 28 in which the pivot pin 29 is located, while in the modification shown in Fig. 7 the hooks and pins are done away 10 with and the projections 30 on one of the jaw members fit and are held within the countersunk portions 31 of the opposite jaw member.

In manufacturing, the jaw members are 15 preferably cast of malleable iron and when assembled together the hook portions of one of the members are sprung outward over the circular projections and pivot pins and into place within the countersunk portions 20 of the other jaw member, the tapering nut of course, being first placed between the jaw members before they are pivotally connected together. After the jaw members have been connected together the locking 25 pins are then secured into position so that they contact with the outer edge or bulged portion of the hooks, thereby securely holding the pivoted jaw members in their closed or contracted position.

- 30 In use the contracted jaw members holding the tapering nut are first placed within the hole formed in the wall. The threaded bolt is then inserted through a hole formed in the object to be secured to the wall and 35 into the jaw members and then screwed into the tapering nut. The further turning of the bolt head causes the nut to feed along the screw threaded portion of the bolt and the tapering side portions of the nut to 40 ably engage with the inner lower tapering portions of the jaw members and cause the jaw members to expand and securely grip the walls of the hole. During the expansion of the jaw members, due to the pressure exerted in turning the bolt head, the outer 45 edges of the hooks that engage with the locking pins become crushed, due to their softness, thereby permitting the expansion of the jaw members when secured to position 50 within the hole of a wall.

Heretofore, expansion bolts have not been securely bound together to prevent the parts from becoming separated and lost during transportation and furthermore lag screws 55 have also been employed, which as is well-known, have no standard thread and on this account it has sometimes proven difficult to successfully operate the expanding jaws. By the use of a device constructed 60 in accordance with this invention it will be seen that I overcome these difficulties and have provided an expansion bolt with pivoted jaw members that cannot become separated and furthermore, that also I have provided a standard bolt and nut for success-

fully operating the expanding jaw at all times.

It is obvious that those skilled in the art may vary the details of construction and arrangements of parts without departing 70 from the spirit of my invention and therefore I do not wish to be limited to such features except as may be required by the claims.

What is claimed as new is:—

1. In an expansion bolt, the combination 75 of a pair of pivoted jaw members provided with bowed and roughened outer surfaces, a threaded bolt passing through the jaw members, a tapering nut mounted on the said bolt and adapted to contact with the pivoted jaw members and arranged for expanding the said jaw members upon the turning of the bolt, said jaw members provided with coacting and interlocking means 80 adapted to prevent the expansion of the jaw members until the threaded bolt is operated.

2. In an expansion bolt, the combination 85 of a pair of pivoted jaw members provided with bowed and roughened outer surfaces, a threaded bolt passing through the jaw members, a tapering nut mounted on the threaded bolt, a locking pin mounted on the pivoted ends of the jaw members, projections 90 mounted on the jaw members and adapted for coacting with the locking pins for holding the pivoted jaw members in the closed position until the turning of the bolt, and a projecting lug mounted on the lower end 95 of one of the jaw members and arranged for contacting with the tapering nut for the purpose set forth.

3. In an expansion bolt, the combination 100 of a pair of pivoted jaw members provided with bowed and roughened outer surfaces, a threaded bolt passing through the jaw members, said jaw members provided with countersunk portions, a locking pin mounted 105 in the countersunk portions, hooks 110 mounted in the countersunk portions for coacting with the projecting lugs for preventing the expansion of the jaw members until the threaded bolt is operated, a tapering nut mounted on the threaded bolt, and lugs mounted on the tapering nut and arranged 115 for contacting with the projecting lug on the jaw member, for the purpose set forth.

4. In an expansion bolt, the combination 120 of opposed jaw members provided with roughened and bowed outer surfaces, one of said jaw members is also provided at its upper end with a circular countersunk projection, a pivot pin mounted on the circular projection, a projecting hook mounted 125 on the upper end of the other jaw member and adapted to fit within the circular countersunk portion and extend around the pivot pin, a locking pin mounted within the 130

countersunk portion and adapted to engage with the projecting hook for holding the jaw members in their contracted position, a threaded bolt passing through the jaw members, a tapering nut mounted on the threaded bolt and arranged for expanding the jaw members upon the turning of the bolt, and means mounted on the tapering

nut for contacting with the jaw members for the purpose set forth. 10

In testimony whereof I affix my signature in presence of two witnesses.

DANIEL MASOR.
